(57) **CLAIM**

The ornamental design for a tire sidewall, as shown and described.

DESCRIPTION

FIG. 1 is a side perspective view of a tire sidewall showing our new design;

FIG. 2 is an enlarged fragmentary side elevational view of the upper right quarter quadrant of FIG. 1; and,

FIG. 3 is an enlarged fragmentary side elevational view of the lower right quarter quadrant of FIG. 1.

The broken lines in the drawings represent unclaimed environmental subject matter.
